(57) **CLAIM**

The ornamental design for a snack bowl as shown and described.

DESCRIPTION

FIG. 1 is a top perspective view of a snack bowl showing my new design;

FIG. 2 is a front elevation view thereof;

FIG. 3 is a rear elevation view thereof;

FIG. 4 is left side elevation view thereof;

FIG. 5 is right side elevation view thereof;

FIG. 6 is a top view thereof; and,

FIG. 7 is a bottom view thereof.

The broken lines in the drawings depict portions of the snack bowl that form no part of the claimed design.

1 Claim, 6 Drawing Sheets
